UNITED STATES PATENT OFFICE.

EMMA L. ANSORGE, OF NEWAYGO, MICHIGAN.

BOX.

No. 911,693.

Specification of Letters Patent.

Patented Feb. 9, 1909.

Application filed March 13, 1907. Serial No. 362,145.

To all whom it may concern:

Be it known that I, EMMA L. ANSORGE, a citizen of the United States, residing at Newaygo, in the county of Newaygo and 5 State of Michigan, have invented a new and useful Improvement in Boxes, of which the following is a specification.

This invention relates to boxes formed of paper and the object of the invention is a 10 paper box adapted especially for use for berries and small fruits.

The invention consists of a box having the sides formed of one piece, and having the bottom formed separately from the sides 15 and interlocked with the sides.

In the drawings forming a part of this specification:—Figure 1 is a view of the blank from which the sides are constructed. Figs. 2 and 3 are views of the blanks from 20 which the two-part bottom is formed. Fig. 4 is a perspective view of the box set up, a portion of the sides being broken out to show the interlocking of the bottom. Fig. 5 is a section upon a reduced scale on the 25 line 5—5 of Fig. 6. Fig. 6 is a plan view of the box. Fig. 7 is a plan view of the modified form of bottom, being formed in one piece instead of two.

In these drawings A represents the strip 30 from which the sides of the box are constructed. These sides are formed by bending the strip A transversely and the strip when bent upon the lines 1, 2, 3 and 4, shown in Fig. 1, is divided into four square 35 sides A', A², A³ and A⁴ and the bend upon the line 1 forms an end flap A⁵ carried by the side A⁴ and this flap is notched upon opposite sides as shown at A⁶ to form tongues A⁷. These sides are cut in order to interlock 40 with the end flap A⁵ or with the bottom of the box in the following manner:—The side A' is provided with two small longitudinally extending and obliquely arranged slots a, which receive the tongues A⁷. 45 The other cuts formed upon the sides are intended to receive certain portions of the bottom of the box to be hereafter described. These slots consist of a curved slot b, formed on the side A'. The side A², is provided 50 with two obliquely transversely arranged slots c, and a longitudinally extending slot c' parallel to the lower edge of the side and between the said edge and the slots c.

The side A³ is provided with one of the 55 curved slots b and the side A⁴ is provided

with the slots c and c' similar to those formed in the side A². The bottom of the box I prefer to form in two sections B and C. The section B is provided with an end flap B', formed by reducing the width of 60 the section B, and this end flap is partially separated from the body portion of the section B by slots B².

The bottom section B is bent along the dotted line B³ and also along the dotted lines 65 B⁴ which last mentioned lines are adjacent side edges of the bottom section and are at right angles to and intersect the line of bending B³. The bottom section is also cut as shown at B⁵, which cuts are made upon 70 the line B³ from opposite sides of the box to the intersections on the line B³ with the lines B⁴. Cuts B⁶ are also formed in the end of the bottom portion B at right angles to the cut B⁵ and these cuts extend to the 75 line B³ and form corner end flaps B⁷ which lie between the cuts B⁵ and B⁶, being joined to the body portion along the uncut portion of the line B³ between the inner ends of the cuts B⁵ and B⁶. This construction leaves 80 an end flap B⁸ between the corner flaps B⁷ which end flap is notched to form oppositely extending tongues B⁹.

The other section C of the bottom differs 85 from the section B mainly in the absence of the end flap B', and its tongue B². It is folded or bent upon the lines C' and C² which correspond exactly with the lines B³ and B⁴. It is provided with an end flap C⁴ and with corner flaps C⁵ corresponding exactly in 90 construction with the corner flaps B⁷ and the end flaps B⁸. The body portion of the section C is formed with obliquely disposed slots C⁶ which receive the tongues B⁹ thus locking the two bottom sections together. 95 The construction of this bottom will be more clearly understood by reference to the modification in Fig. 7 where I have shown a bottom piece constructed exactly like the sectional bottom, so far as its interlocking 100 with the sides of the box is concerned, and which differs from the sectional bottom only in the fact that it is formed out of one piece, therefore, omitting tongues B² and slots C⁶. This one piece bottom D is bent upon the 105 transverse lines D' and upon the longitudinal lines D², is provided with corner flaps D³ and two end flaps D⁴ at opposite ends of the body portion D. It will be obvious therefore, that when the sections B and C are 110

locked together, they form practically the same bottom as is formed by the bottom D.

In assembling the parts together the sides are bent upon the lines 1, 2, 3 and 4 and the 5 tongues A⁷ of the end flap A⁵ are brought into engagement with the obliquely arranged slots a, of the end A'. Either the sectional bottom with the two sections locked together or the one piece bottom D may be employed 10 in connection with the sides A. As the two-part bottom is my preferred form a brief description of the manner in which it is locked to the sides will be sufficient since the one piece bottom is secured in exactly the 15 same manner.

The bottom piece is bent upon the dotted lines thus forming a square bottom having a vertical flange running entirely around it which flange fits within the cube formed by 20 the sides A. The end flaps B³ and C⁴ engage respectively, the slots c' of the sides A² and A⁴. The tongues carried by these flaps, C⁶ and B⁹, engage respectively, the obliquely disposed slots c of the sides A² and A⁴. This 25 locks the bottom in position and the box is complete. It will be obvious from this description that the construction is very simple and that in order to provide the complete box it is only necessary to engage the 30 tongues A⁷ of the sides with their respective slots and the flaps and tongues of the bottom section with their respective slots, and the locking of the box is complete.

The curved slot b forms ventilators adjacent the bottom of the box and permits free 35

access of air to berries and small fruits thereby aiding in preserving them.

Having thus fully described my invention, what I claim as new and desire to secure by Letters Patent, is:—

1. A box of the kind described consisting of sides formed of one piece, said piece being bent to form four sides and an end flap, the end flap interlocking with the side formed by the opposite end of the strip, 45 alternate sides being provided with longitudinal slots adjacent their lower edge, and obliquely arranged transverse slots above the first mentioned slots, and a bottom provided with up-turned corner flaps, and having end 50 flaps provided with tongues, said end flaps being carried by opposite ends of the bottom, the end flaps engaging the longitudinal slots of the sides and the tongues carried by the end flaps engaging the transversely arranged 55 slots.

2. A box of the kind described comprising a strip bent to form four sides and an end flap, said end flap interlocking with one of the sides, and a bottom formed of two interlocking sections, each of said sections carrying an end flap provided with tongues, slots being formed in opposite sides of the box to receive the said end flaps and to receive the tongues, as and for the purpose set forth.

EMMA L. ANSORGE.
